CARBURETOR CONTROL

James P. Farrell, Berkeley, Calif.

Application May 20, 1932, Serial No. 612,533

15 Claims. (Cl. 261—39)

My invention relates to means for controlling a carburetor used in conjunction with an internal combustion engine and is especially useful in conjunction with carburetors on automotive vehicles.

It is customary in starting an internal combustion engine from cold to reduce materially the proportion of air in the fuel-air mixture, and after the engine has arrived at operating temperature to restore the proportions to their running values. An engine after having been started and while still cold can only with great difficulty be idled or run slowly, partly because of the added friction due to viscous oil and also because of various other factors. If the proportion of air and fuel is very carefully regulated, a cold engine can nevertheless be run relatively slowly or alternatively if the air-fuel mixture is not precisely regulated then the engine must be run somewhat faster.

It is therefore an object of my invention to provide an automatic means for permitting an engine to run relatively rapidly when cold.

Another object of my invention is to provide a mechanism which will cause an engine to run relatively rapidly when cold but which will permit the engine to run relatively slowly when it has arrived at its operating temperature.

A further object of my invention is to provide a speed regulating mechanism on a carburetor which is self-contained and is independent of the customary throttle linkage and closure springs.

The foregoing and other objects are attained in the embodiment of the invention shown in the drawings, in which—

Figure 1 is a cross section on a diametral plane of a carburetor throat with the carburetor control of my invention incorporated therewith.

Figure 2 is a cross section the plane of which is indicated by the line 2—2 of Figure 1.

Figure 3 is a plan of a modified form of carburetor control in accordance with my invention.

Figure 4 is a cross section, the plane of which is indicated by the lines 4—4 of Figure 3.

Figure 5 is a cross section on a diametral plane of a still further modified form of carburetor control of my invention.

Figure 6 is a plan of a different form of control suitable for use with the carburetor of Figure 1.

Figure 7 is a side elevation of the mechanism shown in Figure 6.

Figure 8 is a cross section on an axial plane of a different form of carburetor control of my invention.

Figure 9 shows the mechanism of Figure 8 in a different position.

Figure 10 shows the mechanism of Figure 8 in another position.

Figure 11 shows the throttle valve of Figure 8 in plan.

In its preferred form, the carburetor control of my invention is adapted to be used in conjunction with a carburetor adapted to furnish a fluid fuel mixture and which is provided with a valve for preventing flow of said mixture, and includes means for permitting an auxiliary flow under control of a thermostat.

In the form of the device disclosed in Figures 1 and 2 there is illustrated part of the induction mechanism of an engine, in this instance a portion of a standard carburetor having a cylindrical wall 6 defining a carburetor throat 7 through which a combustible fuel mixture is designed to flow in the direction of the arrow 8. The pressure adjacent the arrow 8 is considerably higher than the pressure in the region 9 and causes the flow through the throat 7. The wall 6 merges into a flange 11 provided with suitable apertures 12 for the reception of fastening devices for securing the carburetor to the manifold of the engine with which the device is utilized.

In order to control flow through the throat 7, bosses 14 and 16 formed integrally with the wall are pierced by a throttle shaft 13 on which is mounted a butterfly valve or disc 17, and at one end of which is a lever 18 designed to be connected to the usual throttle operating linkage. Such linkage customarily is manually or pedally impelled in one direction to move the disc 17 to open or non-obstructing position, and is returned to move the disc to closed or obstructing position by means of a relatively stiff and powerful spring. Because of such spring I have found it impractical to provide a mechanism for holding the throttle shaft 13 in slightly open position to give faster idling speeds when the engine is cold.

In lieu of such an arrangement and as an improvement thereover, I preferably pierce the disc 17 with a plurality of conduits or passages 19 which permit flow from one side of the disc to the other by virtue of the difference in pressure and further provide a thermostat 21 so that flow can occur freely through the apertures or conduits 19 when the engine is cold, but will be prevented when the engine is warm.

In the present instance, the thermostat is comprised of a bimetallic disc including a first metal sheet 22 and a second metal sheet 23 having different coefficients of expansion. Since these

sheets are united, under the influence of varying temperature, they snap quickly from one extreme position to a second extreme position through a median planar position. In order that the disc 21 can suitably be held, I preferably pass a bolt 24 through the throttle shaft 13 and through the disc 21 and the butterfly valve 17. The bolt is retained by a suitable nut 26 and, if desired, a washer 27 can be interposed between the disc 21 and the throttle shaft 13. With this arrangement, when the parts are relatively cold the disc 21 assumes the position shown in Figure 1, permitting ample idling flow through the conduits or apertures 19, despite the fact that the main butterfly valve 17 may be in closed position. As the temperature increases due to continued operation of the engine, at a critical value the disc 21 snaps into its other extreme position closely overlying the apertures or conduits 19 and thus acting as a valve to prevent flow therethrough, and thus confining the flow of mixture past the butterfly valve disc 17 simply to the leakage thereby. There is thus provided a mechanism which automatically permits a greater flow of combustible mixture past the butterfly valve when the parts are cold than is permitted when the parts are warm.

I have found in practice that it is usual for the wall 6 of the carburetor throat to expand much differently under variations in temperature than the butterfly valve disc 18 and thus to cause erratic operation, especially erratic idling. To overcome this deficiency I preferably counterbore the carburetor throat wall 6 and insert therein a sleeve 27 of material such as invar. The throttle disc 17 is then also made of invar. Since these parts are of the same material and are of a material which has a relatively low coefficient of expansion, the clearance between the throttle disc 17 and the wall of the throat 7 is maintained substantially constant.

In the event that pulsations and fluctuations in pressure within the throat 7 are sufficient to cause deleterious and audible vibration of the disc 21, I preferably employ in place thereof a mechanism including a balanced valve which inherently is not subject to disturbance by pressure pulsations or fluctuations. As shown in Figures 3 and 4, there is provided a main butterfly valve or disc 28 which is formed with a central aperture 29 for the reception of a fastening means for securing the valve to a throttle shaft such as 13. The disc is likewise pierced by a circular aperture 31, through which, when the aperture is unobstructed, an auxiliary mixture flow can occur. Mounted on suitable trunnions 32 and 33 fixed on the disc 28 is a cross shaft 34 carrying a balanced disc valve 36. The valve is provided with a pitman 39, pivoted thereto, as at 41, which is likewise pivoted as at 42 to the free extremity of a bimetallic thermostatic strip 43. This strip is anchored to the disc 28 by suitable fastening means 44.

In this arrangement when the parts are relatively cold the thermostatic strip 43 maintains the valve disc 36 substantially in the position "A" shown in Figure 4, permitting considerably auxiliary flow through the aperture 31. As the parts increase in temperature, the strip 43 through the medium of the pitman 39 rocks the disc 36 from the position "A" into a position "B" in which the disc is coplanar with the butterfly disc 28, and flow through the aperture 31 is substantially prevented.

After an engine has arrived at operating temperature and has been shut down, fuel flow through the throat of the carburetor has ceased,

but heat radiates thereto from the surrounding parts and causes a further increase in temperature of the thermostatic strip 43. Such additional increase in temperature causes a movement of the disc 36 into a position such as "C". In this position flow through the aperture 31 is again permitted, so that if the engine is again started during the period of increased temperature considerable auxiliary mixture is permitted to flow for starting purposes. As soon as a material flow of air and particularly of cold gasoline or other fuel strikes the thermostatic strip 43, the disc 36 is immediately drawn to position "B" and prevents further auxiliary flow.

In installations in which it is not desirable to mount the mechanism directly on the butterfly throttle valve itself, I preferably provide the structure shown in Figure 5, in which the wall 46 of the carburetor throat 47 is provided with a relatively small passage 38 shunting the butterfly valve 49. Flow through the passage 38 is governed by a balanced disc valve 51 mounted on a shaft 52 and having a depending fork 53 encompassing the free end of a thermostatic strip 56, the other end of which is anchored as at 57 to the wall 46. Access to the passage 38 is preferably gained by removal of a suitable plug 58. When the temperature of the parts is relatively low, the thermostatic strip 56 forces the valve 51 at least to partially open position and permits the passage of an auxiliary flow of mixture around the butterfly valve 49, even through the latter valve is in closed position. However, when the parts are relatively warm the thermostatic strip 56 operates to close the valve 51 and to preclude further flow through the passage 38.

In the form of my invention disclosed in Figures 6 and 7, a throttle disc 61 is provided with a thermostatic strip 62 at one end anchored to a bracket 63 mounted on the throttle disc and at the other end carrying a plate valve 64 adapted to overlie an elongated aperture 66 piercing the disc 61. When the parts are relatively warm the plate 64 fully overlies the aperture 66 and precludes auxiliary flow therethrough, while when the parts are relatively cold the thermostatic strip 62 moves in such a fashion as to uncover part or all of the aperture 66 and to permit auxiliary mixture flow therethrough.

In all of the forms of my device in which the thermostatic element is mounted on the throttle disc itself, it is usually preferable to mount the strip on the high pressure side of the throat so that the incoming stream of air or air and fuel which is relatively cool can maintain the thermostat at a relatively low temperature. Under certain conditions, however, successful results have been obtained by mounting the thermostatic element on the low pressure side of the disc where it is somewhat protected from the incoming stream of fuel mixture.

It is often advisable to provide a mechanism which can be installed in standard carburetors without substantial change thereof, but which will nevertheless be suitable for installation in new designs of carburetors. Such mechanism is disclosed in Figures 8 to 11, inclusive. As shown therein, there is provided a conduit which, for example, is a carburetor throat defined by a wall 71 having flanges 72 thereon pierced by apertures 73 for the reception of fastening devices for securing the mechanism to a suitable support. In the customary way, mixture flows through the passage 74 defined by the wall 71 and is preferably controlled by a throttle or butterfly valve,

generally designated 76. This throttle is preferably mounted on a throttle shaft 77 which is suitably journalled in the wall 71. Rotation of the throttle shaft moves the throttle valve 76 to govern the flow through the conduit 74. As shown in Figure 8, the throttle disc, when on a slight incline, abuts the wall 71 throughout its entire periphery and substantially closes the passage 74.

10 In order that there can be an auxiliary flow through the passage 74 when the engine to which the carburetor control is attached is relatively cold, to increase the idling speed automatically, I preferably fabricate the valve 76 in the form 15 of discs 78 and 79 which are composed of two metals having widely different coefficients of expansion. Preferably, the metal of the disc 79 is invar, while the metal of the disc 78 is brass, for instance. In order that the difference in 20 expansion rates of these metals will be relatively ineffective in the direction of the axis of the shaft 77, I preferably sever the sheet 78 into a multiplicity of strips by a plurality of parallel cuts 81, as disclosed in Figure 11.

25 Because of this construction, when the engine is relatively cold the brass disc 78 is somewhat shorter than the invar disc 79 in the direction of the cuts 81, and therefore causes the valve 76 to take the shape shown in Figure 9, allowing a 30 slight passage between the edge of the valve and the wall 71. It is to be understood that Figures 9 and 10 are both greatly exaggerated, inasmuch as only a small clearance between the valve and the wall 71 is required and obtained. On the other 35 hand, when the engine is in normal operating condition, the valve 76 is substantially as shown in Figure 8. Just after the engine has been run and has been shut down, additional heat radiates to the valve 76. This heat is not dissipated since 40 there is no cooling flow of air and gasoline, so that the temperature of the valve 76 continues to increase. The valve then flexes in a direction to make an additional opening as shown in Figure 10, which assists momentarily in a subsequent 45 start of the engine.

I claim:

1. A carburetor control comprising a carburetor throat through which a fuel mixture flows, a butterfly valve adapted when closed to prevent 50 flow through said throat, said butterfly valve having a conduit therethrough, a valve movable with said butterfly valve for controlling flow through said conduit, and thermostatic means for actuating said valve.

55 2. A carburetor control comprising a carburetor throat through which a fuel mixture flows, a butterfly disc adapted when closed to prevent flow through said throat, said disc having a fuel mixture passage therethrough, and temperature 60 responsive means movable with said disc for controlling flow through said passage.

65 3. A carburetor control comprising a carburetor throat through which a fuel mixture flows, a butterfly disc adapted when closed to prevent flow through said throat, said disc having a fuel mixture passage therethrough, and a thermostat mounted on said butterfly disc for controlling flow through said passage.

70 4. A carburetor control comprising a carburetor throat through which a fuel mixture flows, a butterfly disc adapted when closed to prevent flow through said throat, said disc having a fuel mixture passage therethrough, a valve for controlling flow through said passage, and a thermo-

stat mounted on said butterfly disc for actuating said valve.

5 5. A carburetor control comprising a carburetor throat through which a fuel mixture flows, a butterfly disc adapted when closed to prevent flow through said throat, said disc having a fuel mixture passage therethrough, a valve movable with said disc for controlling flow through said passage, and a thermostat adapted to open said valve in response to a relatively low temperature and to close said valve in response to a relatively high temperature.

10 6. A carburetor control comprising a carburetor throat through which a fuel mixture flows, a butterfly disc on opposite sides of which different pressures exist and adapted when closed to prevent flow through said throat, said disc having a fuel mixture passage therethrough, a valve unaffected by said different pressures for controlling flow through said passage, and a 15 thermostat mounted on said butterfly disc and adapted to open said valve in response to a relatively low temperature and to close said valve in response to a relatively high temperature.

20 7. A carburetor control comprising a carburetor throat through which a fuel mixture flows, an operating shaft spanning said throat, a throttle disc fixed on said shaft, and thermostatically controlled means entirely supported 25 by said disc for lessening the effective area of said disc.

25 8. A carburetor control comprising a carburetor duct through which fuel mixture flows, a transverse shaft spanning said duct, a butterfly valve on said shaft and adapted to be moved from a flow restricting position in close proximity to the walls of said duct to an open position remote from the walls of said duct, and thermally-controlled means unaffected by the proximity 30 of said valve to said walls of said duct for conducting fluid from one side of said butterfly valve to the other side thereof.

35 9. A carburetor control comprising a carburetor duct through which fuel mixture flows, a butterfly valve relatively movable in said duct and adapted by its relative position in said duct to control fluid flow therethrough, means including a passage the cross sectional area of which is independent of the relative position of said butterfly valve for conducting fluid from one side 40 of said butterfly valve to the other side thereof, and thermally responsive means for controlling said conducting means.

45 10. A carburetor control comprising a carburetor duct, a fuel mixture throttling valve 55 therein, said throttling valve having a passage therein, a valve carried by said throttling valve and co-operating with said passage, and temperature responsive means for controlling said valve.

50 11. A carburetor control comprising a carburetor duct, an operating shaft spanning said duct, a fuel mixture throttling valve on said shaft, means supported entirely by said operating shaft 65 for lessening the effective area of said throttling valve, and thermally responsive means for controlling said lessening means.

60 12. A carburetor control comprising a carburetor passage through which a fluid flows, a 70 butterfly valve adapted when closed substantially to prevent flow through said passage, said butterfly valve having a conduit therethrough, a substantially balanced valve movable with said butterfly valve for controlling flow through said 75

conduit, and thermostatic means for actuating said valve.

13. A carburetor control comprising means having therein a main fuel mixture passage, a 5 throttle valve in said passage, means having therein a by-pass passage communicating with said main fuel mixture passage through separate openings spaced apart to lie on opposite sides of said throttle valve, and a thermally responsive 10 valve for controlling fuel mixture flow through said by-pass passage.

14. A carburetor control comprising a carburetor duct, a butterfly valve in said duct for controlling fuel mixture flow therethrough,

means forming a passage having walls which are fixed relative to each other for conducting fluid from one side of said butterfly valve to the other side thereof, and a temperature-responsive valve for controlling said passage.

15. A carburetor control comprising a carburetor passage through which a fuel mixture flows, a butterfly valve in said passage for controlling flow therethrough, a conduit having walls which are fixed relative to each other 10 shunting said butterfly valve, and thermostatic means for varying the effective area of said conduit.

JAMES P. FARRELL.
